W. S. Morris

Inventor
Charles H. Downes
By Atty. C. T. Campbell.

UNITED STATES PATENT OFFICE.

CHARLES H. DOWNES, OF JERSEY CITY, NEW JERSEY.

DESIGN FOR PENCIL-CASES.

SPECIFICATION forming part of Design No. 11,764, dated May 4, 1880.

Application filed April 3, 1880. Term of patent 7 years.

To all whom it may concern:

Be it known that I, CHARLES H. DOWNES, a citizen of the United States, residing at Jersey City, in the county of Hudson and State of New Jersey, have invented and produced a new and useful Design for Pencil-Cases, of which the following is a specification, reference being had to the accompanying drawings, forming part thereof, in which is represented a side view of my newly-designed pencil-case, showing the barrel and nib of the pencil protruding from it.

A designates the cylindrical body of the case; B, the neck thereof, and C the head or cap. F F F are hoops, and g g are handles applied to the body A. These parts constitute the design of the well-known milk-can, as represented in the annexed drawings.

From the center of the head C of the can

protrudes a cylindrical portion, D, surmounted by a ring, a, and centrally from the bottom of the body A protrudes a pencil-nib, b.

Instead of the pencil-nib b, a watch-key, a tooth-pick, or other suitable device may be substituted.

The leading feature of my design consists in the milk-can with a pencil or its fair equivalent combined.

I claim—

The design for a pencil-case herein shown and described, the same consisting of the body A, neck B, and head or cap C, in combination with the cylindrical portion D, ring a, and protruding portion b.

CHARLES H. DOWNES.
